UNITED STATES PATENT OFFICE.

JULIUS A. STOCK, OF CICERO, ILLINOIS, ASSIGNOR TO W. C. RITCHIE & COMPANY, OF CHICAGO, ILLINOIS, A CORPORATION OF ILLINOIS.

THUMB-HOLE-CUTTING APPLIANCE.

1,360,048.

Specification of Letters Patent. Patented Nov. 23, 1920.

Application filed December 31, 1919. Serial No. 348,504.

To all whom it may concern:

Be it known that I, JULIUS A. STOCK, a citizen of the United States, residing at Cicero, in the county of Cook and State of Illinois, have invented certain new and useful Improvements in Thumb-Hole-Cutting Appliances, of which the following is a specification.

This invention pertains to machines of simple, efficient, and durable construction for providing thumb or finger holes in pasteboard box-covers and the like, one of the salient and outstanding characteristics of a desirable physical embodiment of the invention being its capacity for effective and rapid work automatically consummated. Such preferred embodiment of the invention comprises a structure of relatively few parts so designed, arranged, and associated together as to make adjustment of the appliance easily accomplished for operation on box elements of different sizes.

For a full and complete understanding of the invention a machine embodying the same has been illustrated in the accompanying drawings, which should be considered in connection with the following detailed description of the structure, and throughout the various views of such drawings like reference characters refer to the same parts.

In these drawings:

Figure 1 is a fragmentary elevation of the improved appliance;

Fig. 2 is a plan view of the structure;

Fig. 3 is an enlarged central longitudinal section through the head end portion of the sliding shaft and its associated parts on line 3-3 of Fig. 2;

Fig. 4 is an elevation of the means provided for retaining the row of boxes in proper position and relation; and

Fig. 5 is a cross-section on line 5-5 of Fig. 3 with the parts viewed in the direction indicated by the arrows.

By reference to these drawings, it will be seen that the novel appliance may be used as an attachment if desired for a box-cover making machine and the frame of such machine has been supplied with the reference character 20. Secured to such frame and outstanding therefrom horizontally is an angle-bar or bracket 21 to the under horizontal face of which a thin plate 22 is fastened, the securing means being desirably 55 slots and bolts 23, 23 permitting adjust-

ment of the plate crosswise of the bar 21. It should be noted that this plate projects to the left of the element 21 a slight amount, as shown most clearly in Fig. 3, but less than the width of the flanges or rims of the box-covers designed to rest or slide thereon.

In order to prevent the box-covers 27 from falling off of such relatively-narrow ledge or seat, a horizontal bar 24 is positioned in front of the box elements substantially midway of their height, such retaining bar having a bent portion adjustably secured in a socket member 25 supported by and adjustable up and down on a vertical stud 26 upstanding from the frame 20.

The machine is designed and intended to remove substantially semi-circular pieces from the top and bottom horizontally-disposed flanges of the cover, leaving alined or registering similarly-shaped thumb or finger apertures 28 as illustrated in Fig. 2.

The angle-bar or bracket 21 also has another plate 29 secured to its under face on which a relatively-short angle-bar guide 30 is adjustably fastened by screw or bolt and slot connections 31, 31 whereby a chute or passage of the proper width for the box-covers is formed between the parallel upstanding flanges of the opposed members 21 and 30.

In order to impose suitable resistance on the row of covers 27 to maintain them in proper position or relation and to hold them down on their supporting members, the vertical flange of the element 21 has an upstanding rod 32 secured to its outer face by means of screws 33, 33, and an angle-bracket 34 is vertically adjustably supported on such post or rod by the employment of a thumb or setscrew 35, the lower end of the bracket carrying a leaf-spring 36 secured thereto by suitable screws 37, 37, the lower curved end of such spring being adapted to ride or press on the upper faces of the top flanges of the box elements which pass sidewise through the channel between the parts 21 and 30. As is clearly shown, these box-covers abutting against one another are caused to travel or move intermittently with their heads bearing against the left-hand face of the vertical flange of the angle-bar 21, the means for interrupted pushing the boxes along not being shown in the drawings.

Two alined bearings 38 and 39 are adjustably secured by screw and slot connec-

tions 40 and 41 on the frame 20 and a shaft 42 is slidable in such bearings and is encircled by a coil-spring 43 bearing at one end against a collar 44 loose on the shaft and 5 pressing against the right-hand face of bearing 38 and against a collar 45 adjustably fixed to and movable with the shaft, such stop-collar 45 when engaging the adjacent face of the bearing 39 limiting the travel of 10 the shaft and the parts which it carries to the right.

The right-hand end of the cylindrical shaft 42 has a squared portion 46 on which is fixedly mounted a rectangular plate 47 15 provided with a plurality of vertical slots 48 (Fig. 5) accommodating screws 49 by means of which two vertically-spaced blocks 50 and 51 are adjustably mounted on the supporting member 47. The bifurcated part 52 20 of the block 50 has a U-shaped shear-plate 53 fastened to its upper face, such plate between its legs having a space terminating in a rounded portion 54 conforming to the shape of the piece of pastboard to be cut out of 25 the uppermost flange of the box-cover. In similar manner the bifurcated section 55 of the lower member 51 has fastened to its under face a like U-shaped shear-plate 56.

Between the walls of the element 50 a 30 rock-arm 57 is pivotally mounted at 61 and a like, but inverted, rock-arm 58 is pivotally mounted at 62 between the spaced walls of the member 51. Member 57 has a shear-plate 59 secured thereto and adapted to conform 35 in shape to and to coöperate with element 53, and in similar manner the rock-arm 58 is equipped with a shear-plate 60 co-acting with the member 56. The two oscillatory arms 57 and 58 have pivotally connected 40 thereto at 63 and 64 respectively, two curved links 65 and 66 pivotally mounted at their left-hand ends at 67 and 68 on a sleeve 69 45 slidable on and supported by the reciprocating shaft 44 and between the supporting-plate 46 and the adjacent end of the sleeve, a coil-spring 70 is interposed, which surrounds or encircles the shaft 42, as is clearly illustrated.

In order to reciprocate this sleeve, a suitably-driven cam 71 is employed which operates a bell-crank 72 fulcrumed at 73, the upright-arm of such bent lever having an arm 75 pivoted thereon at 74 and the upper end of the bell-crank lever has two lateral 55 extensions 76, 76 on opposite sides of the arm 75 and equipped with opposed screws 77, 77 adapted to bear on opposite edges of the arm 75, thus providing a simple means of angular adjustment between the parts 72 60 and 75. The upper end of the element 75 is bifurcated to straddle the shaft 42, and each of these spaced portions 78 is slotted for the reception of an angular block 79 swiveled on the shaft at 80, thus providing for the 65 necessary relative movement between the

parts to enable the bell-crank to reciprocate the shaft.

The operation of the appliance occurs substantially as follows:

The pasteboard box elements or flanged 70 covers 27, by means, not shown, are advanced intermittently or step by step in a straight row bearing edgewise end to end against one another with their heads sliding on the vertical face of the angle-track 75 or bracket 21, the flanges or rims of such covers projecting to the left, as shown in Figs. 1, 2, and 3. The purpose of this construction being to simultaneously cut out or remove practically semi-circular or other 80 suitably-shaped sections from the edge portions of the upper and lower horizontal flanges or rim sections of the covers in succession as they are fed in series into the field of action of the cutters and while they are 85 temporarily or momentarily stationary, at the proper moment, the cam 71 feeds the sleeve 69 to the right, and, under the expanding action of spring 43, the shaft 42 and the parts which it carries slide to the right until such movement is arrested or stopped by the engagement of collar 45 with the adjacent face of the stationary shaft-bearing 39. When this occurs, the shear-plates 53 and 56 90 and their supports will have been inserted 95 the proper amount in the box-cover 27 in register therewith, as is clearly illustrated in Fig. 3, such cutter plates and their supporting arms straddling or lying on opposite sides of the box-element retaining-bar 24. 100 These shear plates, as is fully shown in Fig. 3, are then located just below the top flange of the cover and just above its bottom flange and are in such position that they constitute bracing or backing means for 105 such flanges or rim sections during the cutting operation. Sleeve 59 continues its sliding movement to the right after the cessation of travel of the shaft, causing the compression of spring 70 between itself and the 110 now immovable plate 47. This relative movement between the elements 69 and 47 through the instrumentality of the curved links 65 and 66 effects the rocking of the 115 pair of members 57 and 58 and their cutter plates or blades 59 and 60 into coöperative action with the parts 53 and 56, thereby cutting out or removing the marginal semi-circular pieces, leaving the opposite thumb or finger holes or recesses 28, 28 which, in the 120 use of the completed box, facilitate the removal of such cover from its associated box-body or so-called box-tray, not shown.

As soon as this cutting function has been completed, the cam causes the retraction of 125 sleeve 69. For a while, the shaft 42 and the plate 47 under the expanding action of spring 70 remain stationary, whereby such travel of the sleeve merely preliminarily separates the rock-arms 57 and 58. When, 130

however, the rear faces of the parts 57 and 58 engage the plates or brackets 50 and 51, further movement of the sleeve to the left, by its action through such arms and their 5 operating links, forces the shaft to the left against the action of spring 43, the collar 45 moving back out of contact with the abutment bearing 39. Thus, all of the parts are 10 retracted or held back by reason of the action of the cam directly on the sleeve and the action of the latter through the curved links, rock-arms, and brackets on the shaft.

When the reciprocating elements have backed away sufficiently from the row of 15 box-covers, these advance another step, carrying the cover just operated upon out of the way and bringing the next uncut box into register or alinement with the cutting mechanism. Thus, the machine operates 20 continuously, requiring practically no attention on the part of the operator, since this attachment is supplied automatically with box-covers and it merely performs the cutting operation specified.

25 From the adjustability of the various elements of the mechanism it will be clear that the appliance can be used to cut or provide finger recesses in covers of substantially different sizes and dimensions, and that the 30 required adjustments or changes are simple in character and can be accomplished with facility and despatch.

The invention is not limited and restricted to the precise and exact structural details 35 illustrated and described, since these are presented by way of example only, and are susceptible of wide changes. It will be appreciated, therefore, that the invention is capable of a variety of embodiments differing more or less in structural characteristics, but all incorporating the fundamental or underlying principles of structure and operation, without departure from the substance of the invention and without the sacrifice of any of its practical benefits and 40 advantages.

I claim:

1. In a cutting appliance of the character described, the combination of a pair of bearings, a shaft slidably mounted in said bearings, a spring encircling said shaft, a collar on said shaft acted upon by said spring and adapted to limit the movement of the shaft toward the work, a support carried by said 50 shaft, a pair of shear members, blocks on which said shear members are mounted adjustable on said support toward and from one another to enable the shear members to be positioned apart a distance conforming to the corresponding internal dimensions of the box-covers operated upon, cutters adapted to co-act with said shear members pivoted on said adjustable blocks, links connected to said cutters, a sleeve slidable on 55 said shaft to which said links are pivoted,

a spring encircling said shaft between said support and sleeve, and cam operated means to reciprocate said sleeve, substantially as described.

2. In a cutting appliance of the character 70 described, the combination of a slidably-mounted shaft, means to press said shaft toward the work, means to limit the movement of the shaft in such direction, a support carried by said shaft, a pair of shear 75 members, means permitting adjustment of said members toward and from one another on said support to enable them to be positioned apart a distance conforming to the corresponding dimension of the box-covers 80 operated upon, cutters adapted to co-act with said shear members pivoted on the adjustable mountings of the latter, and means to operate said cutters and shaft, substantially as described.

3. In a cutting appliance of the character 85 described, the combination of a support, a pair of bracing members fixed to but adjustable toward and from one another on said support to conform to the corresponding 90 dimension of the box-covers to be operated upon, cutters on and adjustable with said bracing means co-acting with said bracing means to remove portions of the opposite 95 rim sections of a series of box-covers in succession, and means to slide said bracing members to cause them to be brought into and out of co-operative relation with said rim sections and to actuate said cutters, substantially as described.

4. In a cutting appliance of the character 100 described, the combination of a support, a pair of bracing members fixed to but adjustable toward and from one another on said support to conform to the corresponding 105 dimension of the box-covers to be operated upon, a cutter for and co-acting with each of said bracing members adapted to remove portions of the opposite rim sections of a series of box-covers in succession, and 100 means to slide said support and bracing members to cause them to be brought into and out of co-operative relation with said rim sections and to actuate said cutters, substantially as described.

5. In a thumb hole cutting appliance of the character described, the combination of a slidably-mounted shaft, means to press said shaft toward the work, means to limit the movement of the shaft in such direction, 120 a support carried by the shaft, a shear-member on said support adapted to be slid thereby into the box element to be provided with the thumb hole, a cutter adapted to co-act with said shear-member movably mounted 125 on said support, and means to actuate said cutter and control the reciprocation of said shaft, substantially as described.

6. In a thumb-hole cutting appliance of the character described, the combination of 130

a slidingly-mounted shaft, means to press said shaft toward the work, means to limit the movement of the shaft in such direction, a support carried by the shaft, a pair of shear-members on said support adapted to be slid into the box-element to be provided with the thumb-holes, cutters adapted to coact with said shear-members pivoted on said support, and means to rock said cutters and controlling the reciprocation of the shaft, substantially as described.

7. In an appliance of the character described, the combination of means normally fixed with relation to one another to enter a box-cover and be positioned adjacent to its opposite walls, means to reciprocate said means, and means to simultaneously cut out holes in said opposite walls, said entering means having recesses for the accommodation of said cutting means, substantially as described.

8. In an appliance of the character described, the combination of means normally fixed with relation to one another to enter a box-cover and be positioned adjacent to its opposite walls, means to reciprocate said

means, and means to simultaneously cut out finger holes in said opposite walls, substantially as described.

9. In a cutting appliance of the character described, the combination of bracing means adapted to bear against a face of the rim of a pasteboard box-cover, means to slide said bracing means to cause it to be brought into and out of co-operative relation with a series of box-covers in succession, and a cutter co-acting with said bracing means to remove a section of the rim of each box-cover to provide a finger recess, and means to operate said cutter, substantially as described.

10. In a cutting appliance of the character described, the combination of a shear member adapted to bear against the face of the rim of a pasteboard box-cover, means to slide said member to shift it into and out of co-operative relation with a series of box-covers in succession, a cutter shaped to conform to said shear member to remove sections of the rim of each box-cover to provide a finger recess, and means to actuate said cutter, substantially as described.

JULIUS A. STOCK.
